Russell R. Kilburn, Pelham Manor, N. Y., and
Bernard D. Ashbaugh, Mount Gilead, Ohio, as-
signors to H-P-M Development Corporation,
Wilmington, Del., a corporation of Delaware

Application September 28, 1944, Serial No. 115,496

Term of patent 14 years

(Cl. D55—1)

To all whom it may concern:

Be it known that we, Russell R. Kilburn and Bernard D. Ashbaugh, citizens of the United States, residing, respectively, at Pelham Manor and Mount Gilead, in the counties of Westchester and Morrow and States of New York and Ohio, have invented a new, original, and ornamental Design for a Molding Machine, of which the following is the specification, reference being had to the accompanying drawings, forming a part thereof, wherein:

Figure 1 is a side elevation of a molding machine showing our new design;

Figure 2 is a side elevation of the molding ma-

chine as viewed from the opposite side thereof;

Figure 3 is a top plan view of the molding machine;

Figure 4 is an end elevational view of the molding machine as viewed from the left hand end thereof with reference to Figure 1;

Figure 5 is an end elevational view of the molding machine as viewed from the right hand end thereof with reference to Figure 1.

We claim:

The ornamental design for a molding machine, substantially as shown.

RUSSELL R. KILBURN.
BERNARD D. ASHBAUGH.
